UNITED STATES PATENT OFFICE.

HENRY JONES, OF DE KALB, ILLINOIS, ASSIGNOR TO MADISON D. SHIPMAN,
OF SAME PLACE.

BUTTON-SETTING MACHINE.

SPECIFICATION forming part of Letters Patent No. 394,579, dated December 18, 1888.

Application filed July 14, 1886. Serial No. 207,988. (No model.)

To all whom it may concern:

Be it known that I, HENRY JONES, a citizen of the United States, residing at De Kalb, in the county of De Kalb and State of Illinois, 5 have invented certain new and useful Improvements in Button-Setting Machines, of which the following is a specification, reference being had therein to the accompanying drawings, in which—

10 Figure 1 represents a perspective view of a button-setting machine with the cover open; also a piece of fabric with button attached; Fig. 2, a side view of part of the machine, taken on the other side. Fig. 3 is a sectional view 15 of my rotary holder, taken at line *xx*, Fig. 1. Fig. 4 is a side view of my rotary holder, showing a modification of the flange or holding devices. Fig. 5 is an edge view of the holder with the openings modified to suit different 20 fasteners which may be used. Fig. 6 shows some of the kinds of fasteners which may be set with my machine by making slight changes in the openings of the holder or form of anvil, according to the kind used. 25 This improvement relates to a button-setting machine; and the invention consists in the peculiar combinations and the constructions and arrangement of parts hereinafter described, and then more particularly pointed 30 out in the claims.

Referring now to the details of the drawings, A and A' represent the two levers of the machine, which are pivoted together in the same way as many other implements of this 35 class. The jaw of the lever A has projecting from and at right angles to the same a stud, *a*, which carries a rotary holder, B, having a flange, *b*, with a series of openings or slits, *b'*, arranged around the same, as clearly shown 40 in the drawings. The flange is thicker near its junction with the web, for a purpose that will be hereinafter explained, or the spring K (shown in Figs. 4 and 5) may be used for the same purpose, in which cases the flange 45 *b* will not be made tapering. The jaw of the lever A' has an anvil, *a'*, formed on it or attached thereto, of a form suited to the kind of fastener to be used.

At D is shown a cover, which is secured to 50 the jaw of lever A by means of a screw or rivet, E, as shown, in such a manner as to al-

low of the cover swinging on the screw so as to uncover the holder B, as shown in full lines in Fig. 1. When in use, it occupies the position shown in dotted lines in the same figure. 55 The central part of this cover rests on the hub of the holder, and as it is made of thin sheet metal there is a certain amount of elasticity in it, which produces a slight friction on the hub, the object of which will be explained 60 hereinafter, or it may be of the form shown in dotted lines at D', Fig. 1.

Attached to the lever A' is a spring-pawl, F, whose free end takes into the teeth of a ratchet-wheel, G, formed on or securely attached to the holder B. Attached to one of the levers is the spring M, for spreading the jaws of the machine after a complete operation.

The jaw of the lever A is formed with an 70 offset, as shown at *c* in Fig. 1, which enables me to bring the stud *a* and the rim of the holder in the same line with the pivot of the jaws, thus avoiding wrenching of the parts and relieving each of the strain that necessarily would occur if the same were out of line. 75

Instead of using two levers, I may in some cases substitute for one of the levers a stand, as shown by dotted lines in Fig. 1, by which it may be fixed to a bench. I should consider such a stand as an equivalent in the following claims for the lever shown in full lines in the drawings.

The operation is as follows: The holder is first filled with the buttons H and fasteners I 85 and the cover replaced, (when one is used,) as shown in dotted lines, when the leather or other material to which the button is to be attached is placed between the jaw of the lever A' and the holder, and then by pressing the 90 handles of the levers together the prongs of the fasteners are pushed through the material, and, coming in contact with the face of the anvil *a'* on the lever A', are clinched, and the button is thus firmly secured. The handles are then opened, which causes the spring-pawl F to act on the ratchet-wheel G and turn the same one tooth, which moves the holder the distance between two slits, and thus by the opening of the handle the holder is 100 turned and another button-fastener is brought in position for use, when the pressing of the

handles together will insert and clinch another fastener, as before. By a succession of these movements all the buttons of a boot may be readily and rapidly fastened to the same.

- 5 When all the buttons have been exhausted from the holder, the cover may be moved away from the face of the same, as shown in Fig. 1, and then the holder may be easily supplied with another series of buttons and fasteners, 10 or the empty holder may be slipped off the stud *a*, and another holder filled with buttons and fasteners may be substituted for it, when another boot may have its buttons attached, as before. The cover *D* has two other functions besides a cover—viz., it serves to keep the holder on the stud, and its friction on the hub of the holder keeps it from turning in the wrong direction when the spring-pawl is moving from one tooth to the other, and is 15 provided with the opening *d* to allow the attached button to slip readily out of the machine after each complete operation.

It will be observed that the flange *b* increases in thickness toward its junction with the web, by which means fasteners and buttons of various shape may conveniently be used, as should the space between the buttons and the fasteners be more in some than in others, if they are pushed farther in the slits, 20 the holder will still keep them securely in place, as before, and also, when the form of cover shown by *D* is used, prevents the buttons or fasteners from being displaced accidentally. When either of the holders having 25 the modified forms of openings shown in Figs. 4 and 5 is used, the form of the spring-cover will be changed to that shown in dotted lines at *D'*, Fig. 1, and instead of holding the buttons in place by the tapering flange *b* the 30 flange may be made straight, or nearly so, and, in lieu of the taper and the spring-cover to hold the fastener or buttons in place previous to being set, springs, as shown at *K* in Figs. 4 and 5, may be employed.

45 I do not limit myself to the exact construction shown, as it is evident that it may be varied considerably without departing from the spirit of my invention.

What I claim as new is—

- 50 1. The combination of two levers pivoted together, a holder carried by one of said levers and formed with an apertured flange at right angles to its web, an anvil carried by the other lever and adapted to bear against the outer face of said flange, a ratchet-wheel on said holder, and a spring-pawl attached to one of the levers for intermittently rotating said holder, substantially as and for the purpose specified.
- 55 2. The combination, in a button-setting machine, of an anvil and a rotary button-holder formed with a flange at right angles to its

web, provided with a series of elastic openings arranged to firmly hold the fasteners against the action of the anvil, and the latter arranged 65 to operate against the outer periphery of the holder at right angles to the axis thereof, substantially as described.

3. The combination, in a button-setting machine, of two levers, a rotary fastener-holder 70 having spring-openings on its outer periphery and carried by one of said levers, an attaching-anvil on the other lever, and mechanism, substantially as described, for pressing said anvil against the outer periphery of said 75 holder at right angles to its axis, substantially as set forth.

4. In a button-setting machine, the combination of the levers *A A'*, pivoted together, a fastener-holder on one of said levers and 80 having on its outer periphery receptacles for the fasteners, an anvil on the other lever and constructed to press against the outer periphery of the holder, a ratchet-wheel on said holder, and a pawl operated by the motion of 85 one of said levers, substantially as described.

5. The combination, in a button-setting machine, of two levers, as *A A'*, an anvil on one of said levers, a rotary fastener-holder having 90 openings to receive the buttons, and a removable cover to hold the fasteners in position, substantially as specified.

6. The combination, in a button-setting machine, of the levers *A A'*, the anvil *a'* on one of said levers, a rotary fastener-holder on the 95 other having a recess to receive the buttons, and a stationary removable spring-cover to inclose the same provided with an opening to allow the buttons to pass out, substantially as described.

7. The combination of a rotatable holder provided on its outer edge with a series of openings to receive the fasteners or button-shanks and mounted on a stud or projection on one of two levers, said lever being formed 105 with an offset, *c*, with a second lever on which is fixed an attaching-anvil, substantially as described.

8. The combination, in a button-setting machine, of a webbed button-fastener holder provided on its periphery or flange with openings to receive the fastener mounted on a stud on one of two levers, said lever being formed with an offset, *c*, and means for giving the same an intermittent rotary motion, 115 with a clinching-anvil on the other lever, substantially as specified.

In testimony whereof I affix my signature, in presence of two witnesses, this 23d day of June, 1886.

HENRY JONES. [L. S.]
